CLAIM

The ornamental design for a display hanger for small articles or the like, as shown and described.

DESCRIPTION

FIG. 1 is a front elevational view of a display hanger for small articles or the like showing our new design;

FIG. 2 is a top plan view thereof;

FIG. 3 is a bottom plan view thereof;

FIG. 4 is a side elevational view taken from the right of FIG. 1;

FIG. 5 is a rear elevational view thereof.
